[57] **CLAIM**

The ornamental design for a separable mitten, as shown and described.

DESCRIPTION

FIG. 1 is a front elevational view of our separable mitten; the rear elevational view is a mirror image thereof;
FIG. 2 is a typical side elevational view thereof; the opposite side elevational view is a mirror image thereof;
FIG. 3 is a top plan view thereof;
FIG. 4 is a bottom plan view thereof;
FIG. 5 is a typical side elevational view of one separable mitten part in which the separable mitten is separated and closed for ease of illustration; and,
FIG. 6 is a typical side elevational view of one separable mitten part in which the separable mitten is separated and opened for ease of illustration.
The characteristic feature of the design resides in the specific configuration of the zipper mounted on the small finger side of both mittens.
